UNITED STATES PATENT OFFICE.

HENRY A. HARRISON, OF SYKESTOWN, NORTH DAKOTA.

RAILWAY-CROSSING SIGNAL.

1,211,841.

Specification of Letters Patent. Patented Jan. 9, 1917.

Application filed March 10, 1916. Serial No. 83,813.

To all whom it may concern:

Be it known that I, HENRY A. HARRISON, a citizen of the United States, residing at Sykestown, in the county of Wells and State 5 of North Dakota, have invented new and useful Improvements in Railway-Crossing Signals, of which the following is a specification.

This invention relates to improvements in 10 railway crossing signals and has particular application to a train controlled signal for use at the intersection of a highway with a railway.

In carrying out the present invention, it 15 is my purpose to provide a train controlled signal for use at the point of intersection of a highway with a railway which will be automatically operated to signaling position by a train approaching the crossing so as 20 to warn the pedestrians and the drivers of vehicles upon the highway of the proximity of the train, and which will be automatically restored to clear position as the train is passing the crossing so that after the train 25 has passed the crossing, traffic over the highway may be resumed with safety.

It is also my purpose to provide a device 30 of the class described which will operate efficiently and effectively under all conditions, which may be installed and maintained at a minimum expense and which will embody comparatively few parts and these so arranged and correlated as to reduce the possibility of derangement to a minimum.

With the above and other objects in view, 35 the invention consists in the construction, combination and arrangement of parts hereinafter set forth in and falling within the scope of the claims.

In the accompanying drawings: Figure 1 40 is a top plan view of a trackway and highway showing my invention installed, Fig. 2 is an enlarged longitudinal sectional view 45 through the signal apparatus taken on a plane parallel with the trackway, Fig. 3 is a similar view taken on a plane parallel with the highway, Fig. 4 is an enlarged top plan view of the signal apparatus with the top wall removed, and Fig. 5 is a detail perspective view of a locomotive pilot showing 50 an attachment for operating the signal.

Referring now to the drawings in detail, 1 designates a railway and 2 a highway intersecting the railway 1. Arranged at the 55 point of intersection of the railway and the highway is a right angular casing 3 having

one leg 4 lying parallel with the trackway and the other leg 5 parallel with the highway. Rotatably mounted in the casing 3 at the juncture of the legs thereof is a drum 60 6 secured to a vertical axle 7 having the ends thereof journaled in the top and bottom walls 8 and 9 respectively of the casing. The top wall 8 is preferably removable to permit inspection and repair of the device. 65 Formed in the top wall of the leg of the casing parallel with the trackway are openings 10 and 11 arranged adjacent to the juncture of the track leg of the casing with the highway leg and at the outer end of the 70 track leg respectively. Pivoted within these slots are levers 12, and connected to the lower end of the lever 12 in the opening 11 is one end of a wire 13 or other flexible element. The opposite end of the wire 13 is 75 wound about the drum 6 as indicated at 15 and anchored as at 16, being terminated at the lever 12 mounted in the opening 10. Journaled in the outer end of the highway leg of the casing is a vertical shaft 17 and 80 secured to the upper end of the shaft is a signal blade 18, while fastened to the lower end of the shaft within the casing is a cross arm 19 intersecting the plane of the signal blade at right angles and connected to the 85 outer extremities of the cross arm are the ends of a wire 20 or other flexible element extending along the highway leg of the casing and having the central portion thereof wrapped about the drum as at 21, said wire 90 being anchored as at 22 to said drum. A coil spring or the like 13' is interposed in the cable or wire 13 to absorb the shock incident to the initial impulse delivered to the lever 12 by a train. 95

The lever in the slot 11 is arranged a suitable distance from the highway while the lever in the slot 10 is disposed immediately adjacent to the highway and when the track is clear the signal blade 18 lies parallel with the highway, while the lever in the slot 11 is in vertical position and the lever in the slot 10 in an inclined position. In Fig. 5 I have shown one form of means for actuating the signal which means comprises preferably an arm 23 rigidly carried by the pilot 24 of a locomotive and fastened at the lower portion thereof and adapted to project laterally therefrom.

When a train approaches the crossing 2 110 moving in the direction of the arrow in Fig. 1 the arm 23 carried on the pilot 24 of

a locomotive engages the arm 11 moving the same forward against the tension of the spring 13', this movement being transmitted through the cable or wire 13 and drum 6 to 5 the lever cable 20 and thence to the signal 18 causing the same to be turned at right angles to the roadway presenting the word "Stop" to view. Of course, it is to be understood that the position of the lever 11 10 is reasonably remote from the crossing so as to give the warning signal in due time. When the locomotive or train reaches a point adjacent the crossing the lever 12, having been moved to vertical position by the setting of the signal, is now returned to the 15 position shown in Fig. 2 which rotates the drum sufficiently to return the signal 18 to non-indicating position to permit traffic to be resumed over the crossing. It will be apparent, of course, that the relative positions 20 of the signal, roadway, and actuating means for the signal may be changed at will without departing from the spirit of my invention, and if desired the signal 18 may be placed 25 in the center of the roadway or to one side as has been shown in Fig. 1. This, of course, will not affect materially my invention. In some instances the wires 13 and 20 need not be anchored to the drum but I find this arrangement to be preferable. Also it is to 30 be understood that the arm 23 shown attached to the pilot 24 is only one form of actuating means for the signal.

While I have herein shown and described 35 the preferred form of my invention by way of illustration, I wish it to be understood that I do not limit or confine myself to the precise details of construction herein described and delineated, as modification and 40 variation may be made within the scope of the claims and without departing from the spirit of the invention.

What I claim as new and desire to secure by Letters-Patent is:—

45 1. A railway crossing signal comprising a right angular casing having one leg lying parallel with the trackway and the other leg parallel with the highway, a drum rotatably mounted in said casing at the junction of the legs thereof, levers pivoted with 50 in the track leg of said casing adjacent to the inner and outer ends of said leg respectively, a connection between said levers and drum whereby the latter will be rotated 55 in one direction in the operation of one of the levers and in the reverse direction in the

operation of the other lever, a vertical shaft journaled in the outer end of the highway leg of said casing, a signal blade on the upper end of said vertical shaft, and connections between said shaft and drum whereby the shaft will be rotated to move the blade to signaling position in the rotation of the drum in one direction and the shaft rotated to restore the blade to normal 60 position in the other movement of the drum. 65

2. A railway crossing signal comprising a right angular casing having one leg lying parallel with the trackway and the other leg parallel with the highway, a drum rotatably mounted in said casing at the juncture of the legs thereof, levers pivoted within the track leg of said casing adjacent to the inner and outer ends of said leg respectively, a connection between said levers and drum where- 70 by the latter will be rotated in one direction in the operation of one of the levers and in the reverse direction in the operation of the other lever, a vertical shaft journaled in the outer end of the highway leg of said casing, 75 a signal blade on the upper end of said vertical shaft, a cross arm connected to the lower end of said vertical shaft, and a flexible connection between the ends of said cross arm and said drum. 80

3. In a railroad crossing signal comprising a right angular casing having one leg lying parallel with the trackway and the other leg parallel to the highway, a drum rotatably mounted at the jointure of said legs, a vertical shaft journaled in said casing, a signal blade mounted on the upper end of the shaft, a cross arm intersecting the plane of the signal blade at right angles and mounted on the lower end of the said 90 vertical shaft, a flexible element attached to one end of the said cross arm and then wound about the said drum, the free end of the flexible element being attached to the opposite end of the cross arm, track trips 100 arranged proximate and remote of the crossing, a flexible element connecting said track trips and said drum, and shock absorbing means associated with one of said flexible elements. 105

In testimony whereof I affix my signature in presence of two witnesses.

HENRY A. HARRISON.
